UNITED STATES PATENT OFFICE.

JOSEPH LOUIS LAZARE RESTANY, OF PARIS, FRANCE, ASSIGNOR TO SOCIÉTÉ RATEAU, OF PARIS, FRANCE, A FIRM OF FRANCE.

AIR-SUPPLY COOLING FOR COMBUSTION ENGINES.

Application filed January 27, 1923, Serial No. 615,276, and in France February 7, 1922.

The present invention relates to means for cooling the air supplied to an aircraft engine fed by air compressed in a rotary compressor driven by a turbine moved by the 5 exhaust gases of the engine according to a well-known method. The object of the invention is to enable the air supply to be easily cooled, while avoiding the inconveniences of other cooling devices known.

10 To these ends and in accordance with the present invention liquid, of course incongealable, is circulated by a suitably driven pump through a radiator arranged in the path of the air supply to the engine and 15 thereafter through a radiator situated in the air stream of the aircraft in order to withdraw heat from the compressed air and transfer it to the ambient atmosphere.

Further, the cooling liquid may be circulated through a cooling jacket surrounding the various stages of the air compressor, in order to cool the air during compression.

The accompanying drawing illustrates diagrammatically and by way of example 25 the arrangement of a unit formed by the turbo-compressor and cooling device.

A pipe *a*, which conveys the compressed feed air from a compressor *b* is enlarged to 30 form a cooling device *c* through which passes an incongealable liquid. After leaving the cooling device *c* the cooled air passes to a carburettor *d* and thence through an inlet pipe *e* to the engine *f*. The products of combustion from the engine *f* are led 35 through a pipe *g* to operate a turbine *h* in a known manner, the turbine *h* being adapted to drive the compressor *b*.

A radiator *i*, situated in the air stream of the aircraft, is connected with the cooling 40 device *c* by pipes *j* and *k* so that the liquid which has become heated in the device *c* may be re-cooled in the radiator *i*, the circulation of the liquid being effected by a pump *l*, mounted in the pipe *k*.

45 From the pipe *k*, a branch pipe *m* is adapted to lead a portion of the cooling liquid to a cooling jacket *n* provided round the rotors of the compressor *b*, and connected with a return pipe *o*, a valve *p* serving to control the distribution of the liquid between the cooling device *c* and the cooling jacket *n*. Finally, a safety valve *q* is adapted to permit escape to the ambient at-

mosphere in the event of the cooling liquid becoming vaporized through any cause.

55 The apparatus works in the following manner:

The cooling liquid is drawn from the radiator *i* by the pump *l* and is then delivered, partly to the cooling jacket *n*, and partly to the cooling device *c*, and thus serves to cool the air both during its compression in the compressor *b* and also during its 60 passage through the cooling device *c* the liquid afterwards returning, by way of the pipes *j* and *o*, to the radiator *i* where it gives up to the ambient atmosphere the heat which it has extracted from the air supply of the 65 engine.

The pump has its shaft *l'* geared at *l''* 70 to the engine shaft.

The advantages of the device are as follows:

1. The co-efficient of heat transmission between the liquid and air, and vice versa, 75 is higher than that between air and air so that the surface of the exterior cooling device may therefore be smaller than in the case of a radiator in which the cooling of the air supply is effected directly by the ambient 80 atmosphere; and the reduction, as far as possible, of the exterior cooling device is just what is desirable in order to lessen its resistance to the forward movement of the aircraft.

85 2. The sectional area of the passages for the cooling liquid is small, and consequently the main frame of the exterior cooling device is reduced.

3. Finally, the exterior cooling device, 90 which is the most important can be constructed like the radiators at present employed in aviation, that is to say streamlined and of thin metal, which was impossible in the case of the old cooling device.

95 It should be noted that, in the foregoing example, the cooling of the feed air takes place simultaneously with the cooling of the air compressor, by means of a branch of the liquid circulating in the cooling devices *c* and *i*, but these coolings might be effected by means of independent circulating systems and radiators.

100 105 The invention, which has been described with more particular reference to a turbo-compressor unit independent of the engine,

is also applicable in cases where the compressor is driven direct by the engine, moreover, the invention is not restricted to the details which have served to describe it, these details having been given merely to facilitate description of the typical embodiment.

What I claim is:

1. The combination with an internal combustion engine on an aircraft, a compressor 10 supplying compressed air to the engine, a cooler composed of two parts, the first part of the cooler being interposed between the engine and the compressor and containing a cooling liquid and having passages 15 through which the compressed air circulates, and the second part of the cooler acting to cool the liquid from the first part by atmospheric air and being passed in the air current caused by movement of the air craft,

and double walls arranged about the compressor to form chambers through which the cooling medium is passed.

2. An apparatus of the character described comprising in combination an internal combustion engine, a rotary air compressor in communication with the engine, a motor connected with the compressor and operated by the exhaust gases of the engine, a cooling device including a part interposed between the engine and compressor for cooling the air passing to the engine, a part surrounding the compressor for cooling the air passing to the compressor, a radiator in communication with both of said parts and means for forcing the cooling medium 30 through the cooling device.

In testimony whereof I affix my signature.
JOSEPH LOUIS LAZARE RESTANY.
